UNITED STATES PATENT OFFICE.

MAURICE MENCHER, OF NEW YORK, N. Y.

SAFETY RAZOR.

Application filed January 7, 1926. Serial No. 79,797.

This invention relates to new improvements in safety razors and particularly to a razor adapted to employ a square blade of substantially resilient material.

5 An object of the invention resides in providing a holder for the blade which will flex the blade in a predetermined manner and rigidly clamp the same between the holder and guard so that one edge will be projected 10 for use while the remaining edges will be inclosed by the holder.

Another object of the invention resides in providing a guard and holding plate for a substantially square blade in which the 15 holding plate is secured to the guard at two spaced points for exerting a clamping action on the blade adjacent opposite end portions, one of which lies between the two points at which the holding plate is clamped 20 to the guard, so that the blade may be properly flexed to give rigidity along one edge portion projected for use and to prevent relative movement of the blade to the guard in clamped position.

25 A still further object of the invention resides in providing a razor structure in which the handle is detachable from the blade holding elements and in which one of the elements is provided with means for cooperating with the handle in a predetermined manner to prevent detachment of the handle from said element after release of the other element secured thereto.

The invention comprehends numerous objects residing in the construction and association of the several parts which are more particularly pointed out in the following detailed description and in the claims directed to a preferred form of the invention, it being 35 understood however that various changes may be made in the size, shape and relation of these parts, without departing from the spirit and scope of the invention as herein set forth.

40 In the drawings forming part of this application:

Figure 1 is a side elevation of the improved safety razor.

Fig. 2 is a longitudinal section through 45 said razor.

Fig. 3 is a sectional view taken on line 3—3 of Fig. 1.

Fig. 4 is a plan view showing the holding plate in open position.

50 Fig. 5 is a transverse sectional view taken on line 5—5 of Fig. 2.

Fig. 6 is a plan view of the blade.

1 indicates a guard member which is substantially square in plan view as shown in Fig. 4, and has one curved end indicated at 60 2 which curves throughout substantially the entire portion at one end of the median transverse plane thereof. The edge portion of this curved end 2 is partially rolled as indicated at 3 in order to provide a smooth 65 surface adapted to guard the free edge of the blade in use and have bearing contact with the surface being shaved. The free edges of this guard member 1 are provided with laterally extending flanges 4 to provide an enclosure for the edges of the blades which are not in use and prevent accidental contact therewith.

A retaining member 5 is hingedly secured as indicated at 6 along one end to one end 75 of the guard member 1, while the opposite end of the retaining member is curved as indicated at 7 for cooperation at its end opposite to the hinge with the curved end 2 of the guard member. The central portion of 80 this retaining member is provided with a substantially square recess 8 from the central portion of which projects a threaded stud 9 adapted to extend through the slotted opening 10 in the central portion of the 85 raised portion 11 of the guard member so that the handle 12 may be threaded thereon. The retaining member is provided with a transversely extending rib 13 between the hinged portion 6 and the recess 8 which is 90 adapted to engage one face of the blade 14 adjacent one edge thereof for holding it in clamped position against the face of the guard, while the opposite end is clamped between the free end of the retaining member 95 and the curved portion 2 of the guard as clearly shown in Fig. 2.

The blade 14 is provided with a substantially square opening 15 the central portion of which is adapted to fit over the substantially square raised portion 11 on the guard member to accurately position the blade relative to said guard member.

At 16, the guard member is provided with a projection having the end terminating in 105 a lateral extension 17 formed with an opening 18 and a slot 19 providing limited communication with said opening. The handle 12 is formed at one end with an annular flange 20 and adjacent to said flange with a 110 cut away portion 21 adapted to permit the insertion of the handle through the slot 19

into the opening 18 of the projection. This flanged end of the handle is also formed with a recess 22 terminating in the threaded bore 23 in order to permit the relative movement 5 of the end of the threaded projection 9 during the movement of the retaining member on hinge 6. The slot 10 is of sufficient dimension to permit the free movement of this projection through the guard member.

10 This razor employs a blade having four sharpened edges as shown in Fig. 6 with the opening 15 located at substantially equidistant points from each edge in order that in the use of the blade, the projection 11 of 15 the guard will position the blade with any desired edge projecting along the rolled end 3 so that the retaining member may be moved into engagement with the blade and the handle 12 threaded onto the stud 9 for 20 drawing the retaining member toward the guard member to the position shown in Fig. 2 for locking the blade preparatory to using the razor. In this operation the retaining member through the fulcrum connection at 25 6 and the connection with the handle through the stud 9 provides a two-point attachment of the retaining member to the guard member with the transverse rib 13 disposed between these points and exerting a substantial 30 pressure on one edge of the blade for retaining it in firm contact with the guard. The connection of the retaining member with the handle causes the free end of this retaining member to engage the opposite edge portion 35 of the blade immediately adjacent the cutting edge and throughout the length of said cutting edge for holding it in firm cooperation with the rolled portion of the guard at its juncture with the end of the 40 curved portion 2. This will flex the blade along a predetermined arc at one side of the median transverse dimension of the blade so that the edge portion presented for use will be maintained in a substantially rigid relation. This permits the use of a blade which 45 is normally and of itself not sufficient to withstand the pressures applied thereto during use.

The remaining portion of the blade at the 50 opposite side of the median transverse dimension from that above stated is preferably held in a substantially flat or slightly curved relation, the curvature of which is different than that of the side of the blade 55 being used. In this way, the blade is held in substantial rigid relation throughout its entire area, while the retaining member 5 in being secured in position to clamp the blade is flexed to a small extent through the fulcrum at 6 and the limiting of its movement 60 toward the guard by the rib 13.

This reflexing of the retaining member brings the free end thereof into a substantially uniform bearing engagement at the 65 edge of the blade to be used while it also

provides a substantially rigid locking of the blade at the point of engagement with the rib 13. The upper end of the projection 11 on the guard member is adapted to seat in the recess 8 of the retaining member in order 70 to prevent disengagement of the blade from this projection which forms the positioning means for the blade.

The handle construction as above described, provides for the retaining of the 75 handle in assembled relation with the guard member when the retaining member is in open position except when the cut away portion 21 is aligned with one side of the slot 19 which will permit the detachment of the 80 handle from the guard member. As it is frequently undesirable to disassemble the handle from the guard, it will be seen that this construction provides this advantageous feature and that at the same time permits 85 the ready and complete detachment of the handle when desired.

Having thus described my invention, what I claim as new is:—

1. A safety razor comprising a guard 90 member having one end curved at one side of its median line, and the portion at the opposite side of said median line being substantially flat, a retaining member, and means for attaching the retaining member to the guard member at a pair of spaced intervals for securing a flexible blade therebetween, said retaining member clamping the blade on the guard member at a pair of 95 spaced intervals at opposite sides of one of the points at which the retaining member is secured to the guard member, said retaining member flexing said blade at one side of a median transverse line in a predetermined manner.

2. A safety razor, comprising a guard member having one curved end, and the other end substantially flat, a retaining member fulcrumed at one end to the last named end of said guard member, means engaging the retaining member and the guard member intermediate the ends for clamping said retaining member to said guard member adapted to mount a blade therebetween, said retaining member being formed for engagement with the blade along its free end, and a point intermediate said free end, and said fulcrum, and adapted to flex said blade at one side of its median transverse dimension on an arc greater than the flexing of the blade at the opposite side of the median line to provide maximum rigidity in secured position, in contact with said guard member to present a cutting edge projecting between the free ends of the retaining and guard members.

3. A handle construction for safety razors, comprising a guard member having a projection extending from one side thereof terminating in a laterally extending foot, said 120

foot being formed with an opening and a slot providing communication with said opening, a retaining member adapted for cooperation with the guard member for clamping a blade therebetween, said retaining member having a threaded projection extending through an opening in said guard member in substantial alinement with the opening in said foot, and a handle having a bearing flange on one end and an adjacent cut away portion adapted for interfitting engage- ment with said foot when the cut away portion of the handle registers with the slot in a predetermined manner, said handle being adapted for threaded cooperation with said stud for locking the retaining member to the guard member, and said foot being adapted to retain said handle in assembled relation with said guard member when the slot and cut away portion are out of registry. 15
In testimony whereof I affix my signature. 20

MAURICE MENCHER.
